UNITED STATES PATENT OFFICE.

HENRY BERRY, OF SHELTON, CONNECTICUT, ASSIGNOR TO THE DERBY SILVER COMPANY, OF SAME PLACE.

DESIGN FOR A BRUSH OR MIRROR BACK.

SPECIFICATION forming part of Design No. 18,944, dated March 5, 1889.

Application filed January 14, 1889. Serial No. 296,297. Term of patent 7 years.

To all whom it may concern:

Be it known that I, HENRY BERRY, a citizen of the United States, residing at Shelton, in the county of Fairfield and State of Connecticut, have invented and produced a certain new and original Design for a Brush or Mirror Back, of which the following is a specification, reference being had to the accompanying drawing, forming a part thereof, which shows a plan view of a mirror or brush back constructed according to my invention.

The leading features of my design consist in the peculiar shape or outline of the backing for the brush or glass and in the shape or outline of the handle which is joined thereto.

A is the backing, the sides *a b* whereof are curved lines, the side *a* curving regularly, or nearly so, to the point *c*, the side *b* curving more sharply and turning outward in a short curve, *d*, to the point *c*. On the lower end of the backing is the representation of a three-part scroll figure, *e*. The handle *B*, which is joined to the lower end of the backing, is swelled outwardly at its upper end, as at *f*,

tapers and curves downwardly therefrom, and is at its end turned into a loose ammonite shape, *g*. Its surface is fluted, as at *h*, in lines which follow the general conformation of the handle.

The detail ornamentation of the handle and the scroll upon the backing are not the leading features of my design, which, as heretofore stated, principally reside in the outline of the back and handle.

I claim—

The design for brush or mirror backs, the same consisting of the oval-shaped backing, largest at its outer end and terminating in the point *c*, and having the swelled and curved handle joined thereto at the small end of said backing, substantially as shown and described.

In testimony whereof I affix my signature in presence of two witnesses.

HENRY BERRY.
